UNITED STATES PATENT OFFICE.

MELVIN A. YEAKLEY, OF CANTON, OHIO, ASSIGNOR TO JOHN E. McLAIN, OF CANTON, OHIO.

TROLLEY-CATCHER.

1,146,834.

Specification of Letters Patent. Patented July 20, 1915.

Original application filed June 1, 1908, Serial No 436,147. Divided and this application filed December 18, 1913. Serial No. 807,487.

To all whom it may concern:

Be it known that I, MELVIN A. YEAKLEY, a citizen of the United States, residing at Canton, in the county of Stark and State of Ohio, have invented certain new and useful Improvements in and Relating to Trolley Catchers, of which the following is a specification.

This invention relates to means for maintaining a trolley rope taut as the trolley end of the trolley pole moves up and down to adapt itself to different heights of the wire, and to catch and hold the paying out device for the trolley rope when such paying out becomes unduly rapid as when the trolley jumps the wire. Such means are commonly known as trolley catchers.

One object of my invention is to provide means for maintaining the stopping means in operative relationship after the rope winding drum has been stopped.

Another object of my invention is to provide a spring, which is at all times active, for maintaining the stopping means in operative relationship after said means have acted to stop the drum.

Another object of the invention is to provide a dog carrying member, separate from the drum but connected thereto by positive and yieldable means which permit a predetermined relative movement between the drum and said member, whereby the yieldable means operate to maintain the drum stopping means in operative relationship after the drum has been stopped.

With these and other objects in view, the invention consists in the parts and combination of parts hereinafter described and referred to in the appended claims.

This application is a division of my application, Serial No. 436,147, filed June 1, 1908.

For the purpose of illustrating my invention, I have selected and hereinafter described one construction embodying it.

Figure 1 is a vertical sectional view of a trolley catcher embodying my invention, on the line 1—1, of Fig. 2 looking from the right. Fig. 2 is a section on the line 2—2 of Fig. 1 looking from the left. Fig. 3 is a view similar to Fig. 4 with dog and counter-weight removed. Fig. 4 is a section on the line 3—3 of Fig. 1 looking from the left.

Fig. 5 is a sectional view, partly on the line 5—5 and partly on the line 5'—5' of Fig. 1. 55 Fig. 6 is a fragmentary sectional view illustrating the manner of connecting the trolley rope to the drum and the pawl and ratchet devices for locking drum against rotation.

Referring to the drawings, the casing for 60 the mechanism is divided vertically and the two halves 1 and 2 thereof are held together by a bolt 3 which also serves as an axle for the interior mechanism. When assembled the casing has an opening 4 through which 65 the trolley rope 5 passes and there is an opening 6 beneath the winding drum 7. The winding drum 7 is journaled on the bolt 3. Also journaled on the bolt 3 is the dog-carrying member 8 which is separate from the 70 drum and between which driving connection is established in the manner hereinafter described.

The member 8 is provided with pivot pins 10 and 11, which are located on opposite 75 sides of its center. Upon these pins are respectively pivoted the centrifugal dog 12 and its counterweight 13. The dog and counter weight are connected by a spring link 14. A spring 15, coiled about the pin 80 10 and engaging at one end with the dog 12 and at the other end with the member 8, tends to hold the dog out of engagement with the teeth 16 of the ratchet upon the inside of the casing. Upon undue speed the 85 force of the spring 15 will be overcome by the centrifugal operation of the dog and the dog 12 will engage with the ratchet teeth 16. The utility of the counter-weight will be apparent when it is considered that the bolt 90 3 is horizontal and that therefore in the position shown (see Fig. 4) the weight of the dog opposes the centrifugal force. When the dog-carrying member has turned through 180 degrees and the dog occupies the position shown in the drawing as occupied by the counterweight, the weight of the dog 95 will be added to the centrifugal force in producing a tendency for it to move outward.

With the counterweight and the dog linked 100 together, as shown, their weights are balanced at all times so that gravity has no influence upon the dog, which responds solely to the centrifugal force. The counterweight might also be adapted to act as a dog but 105 ordinarily one dog will prove sufficient. The

link 14, being of spring material, the parts are not hampered in their movements as would be the case if this link were rigid.

The spring 26 is for turning the drum 7 to maintain the trolley rope 5 taut as the trolley adapts itself to varying heights of the trolley wire. This spring engages at one end with the hub of the winding drum and at the other end is secured to a segmental spring 27 which slidably engages the interior of the casing. The engagement of the inner end of the spring 26 with the hub of the winding drum is preferably accomplished by bending the end of the spring 26 into a recess as is clearly shown in Fig. 5. The side of this recess against which the bent end of the spring is drawn when the spring is wound is at a somewhat abrupt angle with the bottom of the recess so that movement of the end of the spring 26 in this direction is arrested. The other side of the recess, however, is a gradual incline, as shown, so that if the parts are turned to unwind the spring 26, the end of the spring 25 will slide out of the recess and about the hub, thereby preventing breakage of the spring in case an attempt is made to wind it in the wrong direction. The manner of securing the other end of the spring 26, 30 timely, by means of the segmental spring 27 sliding upon the interior of the casing, prevent the too tight winding of the spring. If an attempt is made to wind the spring beyond a certain tension, the segment 27 will slide and prevent it. In some circumstances the friction between the segment 27 and a smooth casing interior might be sufficient, but it is preferred to provide teeth 28, as shown, upon the casing; in the recesses between which the projection 29 upon the segment 27 extends. Upon a too tight winding of the spring, this projection will be withdrawn from the recess in which it may be located and the segment will slide about the interior of the casing and relieve the surplus tension.

Encircling the bolt 3 is a plate 18 having a ratchet 19 upon its hub. The hub of the plate 18 is preferably loosely sleeved over a reduced portion of the hub for the drum 7. The plate 18 and its ratchet are held against rotation by means of a projection 20 which projects into a recess 21 in the casing. Pivoted at 22 upon the winding drum is a pawl 23 having its nose normally held in engagement with the ratchet 19 by means of a spring 24 which is coiled about the pivot 22 and has one end in engagement with the drum while the other end is in engagement with the tail of the pawl, as shown. The tail of the pawl extends over a hole 25 in the drum. This hole is key-hole shaped, that is, is wider at one end than at the other (the wide end being at the right hand in Fig. 5). The knotted end of the trolley

rope may be passed through the wide portion of the hole 25 and the rope being then drawn into the narrow portion after the knot has been passed within the drum, the end of the rope is securely fastened to the drum by reason of the fact that the knot cannot pass through the narrow portion of the hole. Furthermore, the knot operates to elevate the tail end of the pawl 22, thereby throwing its nose out of engagement with the ratchet 19.

9 indicates connections between the drum 7 and dog-carrying member 8. These connections are constructed to permit movement of the member 8 relative to the drum under certain conditions of operation in order that the centrifugal dog 12 may be maintained in operative position during rebound of the trolley as will be hereinafter set forth. The connections 9 preferably comprise a set of lugs or projections 7^a carried by the flange of the drum, which lugs may be equally spaced from each other, and sets of arms 8^a, 8^b, projecting radially from the periphery of the dog-carrying member 8 and into the path of movement of the lugs 7^a. As will be understood from Figs. 3 and 4, each lug 7^a is arranged between and cooperates with the adjacent arms 8^a, 8^b, constituting one of said sets, to positively drive the dog-carrying member in one direction or the other; that is to say, when the drum rotates in an anti-clockwise direction, the lugs 7^a will engage the arms 8^b and drive the member 8 in the same direction; when the drum rotates in a clockwise direction the lugs 7^a will engage the arms 8^a and drive the member in a clockwise direction. From the construction just described, it will be seen that the dog-carrying member 8 and drum 7 are movable relative to each other on the bolt 3, the distance that the arms 8^a, 8^b, of each set are spaced from each other. In operation, when the trolley pole jumps or leaves the overhead wire, the drum 7 will be rotated in clockwise direction at high speed. The drum 7 will in turn rotate the dog carrying member 8 through the connections 9. Under the influence of centrifugal force thus set up, the dog 12 will swing outwardly, engage one of the teeth 16 and arrest the drum 7, thus preventing further unwinding of the rope 5 therefrom.

9' indicates a spring which flexibly or yieldably connects the drum 7 and dog-carrying member 8 together. The spring 9' operates, as will be later described, to move the said member relative to the drum 7, whereby the dog 12 will be maintained in operative position upon rebound of the trolley pole after it has been arrested. The spring 9' is looped about a pin 17 upon the drum spider. The outer leaf 9^x of this spring 9' is coiled about the hub of the

member 8 and its end is secured thereto by being bent into a recess in the hub, as shown at 9^a. The inner leaf 9^b is unsecured, other than at the looped end, except as it is 5 confined and bound by the outer leaf. It will be apparent that as the pin 17 moves in a clockwise direction relative to the dog carrying member 8, (viewing the parts as shown in Fig. 3), which operation takes 10 place when the rope 5 starts to unwind from the drum and continues until the lugs 7^a engage the arms 8^a, the end of the inner leaf of the spring 9 will be bound between the outer leaf and the hub member 8, so that the 15 spring as a whole will be stiffened and placed under tension. As long as the drum 7 continues to rotate in clockwise direction and the lugs 7^a are driving the member 8 by engagement with arms 8^a, the spring 9' will 20 be maintained under tension as just described. As a result of the sudden stopping of the trolley pole due to engagement of the dog 12 with the teeth 16, the trolley pole may rebound slightly and cause slack 25 in the rope 5. During this rebound, the spring 26 exerting its influence upon the drum 7, rotates said drum in anti-clockwise direction to take up the rope slack. This operation of the drum 7 releases the 30 spring 9' and permits it to unwind or expand. In so doing, the spring 9' tends to rotate or exert a pressure on the dog-carrying member 8 in the opposite direction, that is, clockwise, the effect of which is to prevent immediate anti-clockwise rotation of 35 said member and to maintain the dog 12 in operative position relative to the ratchet tooth it engages to stop clockwise rotation of the drum 7. It will thus be seen that the 40 stoppage means will remain in condition to immediately stop clockwise rotation of the drum during the rebound of the trolley pole, so that when the trolley pole again swings upwardly it will be at once arrested. If the 45 dog 12 were mounted on the drum 7, the rotation of the latter would result in the backing off of the dog 12 from the ratchet 16, whereupon the dog would be retracted and the drum and trolley released, but as 50 the spring 9' acts through the member 8 to retain the centrifugal dog 12 in the path of or in contact with the tooth with which it has been thrown into engagement, the mechanism is adapted to instantly stop further upward travel of the trolley pole after 55 it has rebounded or been forced downwardly and again starts to swing upwardly. The rebound of the trolley pole occupies such a short interval of time that the dog 12 under control of the spring 9' is not moved materially, if at all, from the path of the ratchet tooth and is therefore ready to engage the ratchet tooth before or the instant the pole starts upwardly after the rebound. 60 Furthermore, when the trolley has left the overhead conductor and the trolley pole has been stopped by the action of the catcher from further upward travel of the trolley, should the said pole engage with a span wire, or any superstructure for the overhead conductor and have its trolley end forced downwardly, the winding drum 7 will instantly and freely act to wind up the trolley rope slack and when the said trolley pole is again free to swing upwardly at its trolley end, 65 such movement will be immediately stopped by the engagement of the dog 12 with the ratchet 16, which has been retained in readiness for instant stoppage action. In this construction the spring 9' is made very light 70 and thin, it being intended simply for the purpose of exerting pressure on the member 8 to prevent its rotation and retain the centrifugal dog 12 in the path of the ratchet 16 during the winding up action of the drum 7 when a rebound of the trolley pole occurs, 75 serving the purpose of adapting the operation of the centrifugal dog to act substantially instantly after the rebound of the trolley pole, following the action of the device in stopping the upward travel of the 80 said pole.

Any suitable means may be provided for securing the apparatus to a car. Referring to the means herein disclosed, the right hand 85 end of the case (as viewed in Fig. 1) is provided upon its exterior with the ribs 30, from any suitable number of which extend projections 31. To the car is fastened a bracket or other device (not shown) which 90 is formed with a recess and a circular rim having suitable notches and undercut recesses to receive the projections 31. In this manner bayonet joints are formed which secure the bracket and trolley catcher together. To secure the catcher and bracket in 95 locked relation, an arm 37 extends from the casing of the catcher and in this arm is mounted a slidably bolt 38 which, when the catcher is in locking position upon the bracket, will register with a socket in the rim of the bracket, and the bolt 38 being inserted in this socket, the catcher is locked 100 in position on the bracket. The ribs 30 rest upon the interior of the bracket rim. Any 105 available number of ribs may be employed.

In the operation of the catcher, assuming that the slack-absorbing spring 26 is unwound, possibly the simplest manner of winding it up and placing the catcher in 110 condition for operation, is to loop a section of the trolley rope around the drum 7, then holding the respective ends of the loop firmly in either hand, to seesaw the rope back and forth around the drum, bearing against the periphery of the drum when pulling in the direction to wind the said spring 26, and easing up when pulling in the reverse direction. This is continued until a clattering or chattering noise is heard 115

120

125

130

- which indicates that the segment 27 is slipping about the interior of the casing. The loop of the trolley rope is then withdrawn from the catcher and the lower knotted end 5 of it is introduced through the rope opening 25 and the cord is drawn back into the narrow part of said opening so as to throw the said knotted end against the free end or tail of the pawl, simultaneously swinging 10 the nose of the pawl out of engagement with the ratchet 19 and releasing the drum and its slack absorbing spring; the latter then acts to rotate the drum and wind up the desired amount of trolley rope upon the 15 drum.

When the catcher is not in use and the trolley rope is removed, the spring 26 would quickly unwind, necessitating rewinding before it could be placed in use, unless means 20 were provided for preventing it. In the apparatus shown, when the knot of the trolley rope is removed from the hole 25, the nose of the pawl 23 is thrown into engagement with the stationary ratchet 19 so that 25 the spring is prevented from unwinding. When, however, the catcher is placed in service the pawl 23 is removed from the ratchet 19 upon the insertion of the knot of the trolley rope beneath the tail of the pawl, then the 30 drum is free to move under the action of the spring and maintain the trolley rope taut under the raising and lowering of the trolley in adapting itself to varying heights of the trolley wire. If, however, the trolley 35 should leave the wire the drum would rotate at such a rate that the dog 12 would fly outwardly into engagement with the stationary ratchet 16, whereupon the drum would be stopped and the trolley caught.

40 To those skilled in the art of making apparatus of the class described, many alterations in construction and widely differing embodiments and applications of my invention will suggest themselves, without departing from the spirit and scope thereof. My disclosures and the description herein 45 are purely illustrative, and are not intended to be in any sense limiting.

What I claim is:

50 1. In mechanism of the class described, the combination of a drum, means for rotating said drum in one direction, devices having connection with said drum for stopping the rotation of the drum when the trolley pole swings upwardly, and means for maintaining the stopping devices in operative relation during rebound of the trolley pole.

55 2. In mechanism of the class described, the combination with a casing, of a drum, means for rotating said drum in one direction to wind the rope thereon, means interposed between said drum and casing for stopping the rotation of the drum in rope paying out direction, the said means including a member angularly movable relative

to said drum, and means acting on said member for maintaining the stopping means in operative relationship during rebound of the trolley pole.

3. In mechanism of the class described, the combination with a casing, of a drum, means for rotating said drum in one direction to wind the rope thereon, means interposed between said drum and casing for stopping the rotation of the drum in rope paying out direction, the said means including a pawl device, a ratchet device and a member angularly movable relative to said drum and carrying one of said devices, and means acting on said member for maintaining the stopping means in operative relationship during rebound of the trolley pole. 75

4. In mechanism of the class described, the combination with a casing, of a drum, means for rotating the drum in one direction to wind the rope thereon, means interposed between said drum and casing for stopping the rotation of the drum in rope paying out direction, the said means including a member angularly movable relative to said drum, and a spring acting on said member for maintaining the stopping means in operative relationship during rebound of the trolley pole. 85 90

5. In mechanism of the class described, the combination of a drum, means for rotating said drum in one direction, devices having connection with said drum for stopping the rotation thereof when the trolley pole swings upwardly, and separate means for maintaining the stopping devices in operative relation during rebound of the trolley pole. 95 100

6. In mechanism of the class described, the combination of a drum, means for rotating said drum in one direction to wind the rope thereon, devices having connection with said drum for stopping the rotation of the drum when the trolley pole swings upwardly, and flexible means arranged to be placed under tension by rotation of the drum in rope unwinding direction for maintaining the stopping devices in operative relation during rebound of the trolley pole. 105 110 115

7. In mechanism of the class described, the combination of a drum, means for rotating said drum in one direction to wind the rope thereon, devices having connection with said drum for stopping the rotation of the drum when the trolley pole swings upwardly, and a spring arranged to be placed under tension by rotation of the drum in rope unwinding direction, for maintaining the stopping devices in operative relation during rebound of the trolley pole. 120 125

8. In mechanism of the class described, the combination of a drum, means for rotating said drum in one direction, a rotatable member, connections between said drum and said member for driving the latter, devices, 130

one of which is carried by said member for stopping the rotation of the drum when the trolley pole swings upwardly, and means for maintaining the stopping devices in operative relation during rebound of the trolley pole.

9. In mechanism of the class described, the combination of a drum, means for rotating said drum in one direction, a rotatable member, connections between said drum and said member for driving the latter, devices, one of which is carried by said member for stopping the rotation of the drum when the trolley pole swings upwardly, and flexible means for maintaining the stopping devices in operative relation during rebound of the trolley pole.

10. In mechanism of the class described, the combination with a casing, of a drum, means for rotating said drum in one direction, a rotatable member, connections between said drum and said member for driving the latter, devices, one of which is carried by said member, for stopping the rotation of the drum when the trolley pole swings upwardly, and means arranged to act on said member for maintaining the stopping devices in operative relation during rebound of the trolley pole.

30 11. In mechanism of the class described, the combination of a drum, means for rotating said drum in one direction to wind the rope thereon, a rotatable member, connections between said drum and said member for driving the latter, devices, one of which is carried by said member, for stopping the rotation of the drum when the trolley pole swings upwardly, and flexible means acting independently of said drive connections for maintaining the stopping devices in operative relation during rebound of the trolley pole.

45 12. In mechanism of the class described, the combination of a drum, means for rotating said drum in one direction, a rotatable member, connections between said drum and said member for driving the latter, devices, one of which is carried by said member, for stopping the rotation of the drum when the trolley pole swings upwardly, and flexible means acting independently of said drive connections for maintaining the stopping devices in operative relation during rebound of the trolley pole.

50 55 13. In mechanism of the class described, the combination of a drum, means for rotating said drum in one direction, a rotatable member, connections between said drum and

said member for driving the latter, but permitting relative movement between said drum and member, devices, one of which is carried by said member, for stopping the rotation of the drum when the trolley pole swings upwardly, and flexible means acting on said member independently of said drive connections for maintaining the stopping devices in operative relation during rebound of the trolley pole.

14. In mechanism of the class described, the combination of a drum, means for rotating said drum in one direction to wind up the rope thereon, a rotatable member, connections between said drum and said member for positively driving the latter, means, including a pawl carried by said member, for stopping the rotation of the drum, and a spring connecting said drum and member together and acting through said member to maintain the stopping means in operative relation during rebound of the trolley pole.

15. In mechanism of the class described, the combination of a drum, means for rotating said drum in one direction to wind up the rope thereon, a rotatable member, connections between said drum and said member for positively driving the latter, the said connections permitting relative movement between said member and said drum when the direction of rotation of the latter changes, means, including a pawl carried by said member, for stopping the rotation of the drum, and a spring connecting said drum and member together and acting through said member to maintain the stopping means in operative relation during rebound of the trolley pole.

16. In mechanism of the class described, the combination of a spring, a rotatable member provided with a pair of arms, a drum connected to and operated by said spring to wind the trolley rope thereon, said drum being provided with a lug arranged to engage one of said arms whereby said member is rotated in one direction or the other by said drum, means acting on said member for stopping the rotation of the drum, and a separate spring for controlling the rotation of said member during rebound of the trolley pole to maintain the stopping means in operative relation.

In testimony whereof I affix my signature, in the presence of two witnesses.

MELVIN A. YEAKLEY.
